UNITED STATES PATENT OFFICE.

LUDWIG GETTELmann, OF SOUTH GERMANTOWN, WISCONSIN.

BEET-TOPPER.

No. 861,511.

Specification of Letters Patent.

Patented July 30, 1907.

Application filed November 24, 1906. Serial No. 344,826.

To all whom it may concern:

Be it known that I, LUDWIG GETTELmann, a citizen of the United States, and a resident of South Germantown, in the county of Washington and State of Wisconsin, have invented certain new and useful Improvements in Beet-Toppers; and I do hereby declare that the following is a full, clear, and exact description thereof.

My invention has for its object to provide simple and durable machines for topping beets, the arrangement of the mechanism being such that it will operate effectually to top the beets, under various climatic conditions to which they are subjected at the time of harvesting, said machine being also capable of operating perfectly in all kinds of soil.

The invention therefore consists in certain peculiarities of construction and combination of parts as hereinafter fully set forth with reference to the accompanying drawings and subsequently claimed.

20 In the drawings: Figure 1 represents a side elevation of a beet-topping machine embodying the features of my invention, the view being shown with parts broken away and parts in section to better illustrate the details; Fig. 2, a plan view of the same with the hounds 25 tongue and accompanying parts constituting the draft-rigging removed, as well as the gear-cover, there being other parts in section and broken away to more clearly show the invention; Fig. 3, a detail sectional elevation of the machine looking from the elevator side, the section being indicated by line 3—3 of Fig. 2; Fig. 4, a detail plan view of the draft-rigging comprising the tongue, hounds, etc., detached from the machine; Fig. 5, an enlarged detail section of the topping-apparatus with the adjacent beet-top elevator in elevation, the 30 section being indicated by line 5—5 of Fig. 2; Fig. 6, a detail plan view of the cutting disk and its accompanying stripping-mechanism, the disk-apron being in section upon a plane, as indicated by line 6—6 of the preceding figure; Figs. 7 and 8, plan and edge views respectively of a fragment of the cutting-disk, showing the peculiar formation of the cutting-teeth, and Figs. 9 and 10, are sections of the same as indicated by lines 35 9—9 and 10—10 respectively of Fig. 7.

Referring by letter to the drawings, A indicates the 40 main axle, supported by wheels B, that are provided with lugs a riveted to the wheel-rims to insure traction in all kinds of soil. The main frame C of the machine is mounted upon the axle, being similar in construction to that of an ordinary mower, and having a forward projecting split sleeve b, which forms bearings for a counter-shaft D, which shaft is in bevel-gear connection with a train of gears c, c', d, d', the gear d' being fast on the axle A, whereby motion is transferred to the train from the traction-wheels. The lower end of sleeve b, 45 terminates in arms having vertical boxes e, e', that support an arbor E, which is driven by a bevel-gear wheel

F, fast thereon and in mesh with a bevel-pinion G, secured to the counter-shaft D, the upper box e being formed with a hood f that protects the bevel-gear F from entanglement with beet-tops. The lower end of arbor E is formed with a hub g, which has radial fingers H projecting therefrom that are curved upward and also backward from the direction of the rotation of said arbor, these fingers serving to catch the beet-tops and deliver the same to an elevating-apparatus to be 65 hereinafter described.

A concavo-convex disk I is secured to the lower face of the hub g, having its convexed face presented towards the ground, and its cutting-edge formed with saw-teeth h, as best shown in Figs. 8, 9, and 10 inclusive of the drawings. The arbor E is set at a right-angle to the forwardly inclined sleeve portion of the main-frame, and owing to said inclination the front cutting-edge of the disk is tilted downward having the body of said disk flared up and away from the ground to form a 70 75 clearance which will thus prevent liability of the aforesaid disk coming in contact with the severed beets or uneven ground.

The teeth h are beveled to circumferential knife-edges from point to point of abrupt faces i, the intersecting line of the bevel with relation to the upper face of the disk being tapered backward to the base of the face i of the following tooth to form notches, which notches have their abrupt faces presented toward the rotations of the disk, and serve to catch any dead leaves 80 85 of the beet-tops and carry the same to a point of discharge as said disk revolves. The notches also insure the cutting of the leaves and tops as well as clearing the knife of any particles that may cause the same to choke, and by the peculiar formation of the teeth, the 90 said knife can be readily sharpened by unskilled labor without removing the disk.

When the tops of the beets are severed they fall upon the disk and are caught between the fingers H, which, owing to their rapid rotation, by centrifugal force, 95 throw said tops outward upon an elevator-chain J, that is arranged in an elevator-frame K directly adjacent to the discharge side of said disk.

The elevator-frame K consists of parallel angle-iron bars secured to the main-frame C, by straps j. The 100 lower ends of these bars terminate adjacent to the cutting-disk and have bearings for a roller k, over which the elevator-chain J travels, the chain being driven at the opposite end of the frame by sprocket-wheels m, through gear-wheels n, n', which are fast on shafts p 105 and o. Said shaft o and a shaft p that carries the sprocket-wheels m are supported in brackets q, secured to the angle-iron bars of the elevator-frame. The shaft o also carries a sprocket-wheel r fast thereon that is in link-belt connection with another sprocket s fast on 110 the main-axle of the machine, from which said elevator receives its drive.

While the cutting disk is in motion as previously stated, the severed tops are thrown upon the elevator and thereby delivered to a carrier L. In order to prevent said tops from snarling in the fingers II and being carried past the point of delivering, a stripper I' is secured to the elevator-frame having its end curved towards the center of said cutting-disk between the upper face thereof and said fingers, in such a manner as to form a stationary cam, which serves to deflect the beet-tops clear of the aforesaid disk, it being understood that the stripper, if desired, may be fastened to the main-frame C of the machine in place of the elevator.

The carrier L is hinged and supported upon a frame N having arms secured to the machine, said carrier being supported at the rear by a caster-wheel O. The hinged construction of the carrier permits the operator to dump the tops at will outside of the path of the traction-wheel upon its return travel in cutting the next row of beet-tops.

20 All of the parts heretofore described combined constitute what may be termed the truck of the machine, and the draft-rigging connected thereto is composed of a pole or tongue P, having hounds Q, which hounds are secured to ears t of boxes u loosely mounted upon the main axle, the tongue being also provided with the usual supporting bar R on which is fastened a seat. Secured to one of the hounds is a notched segment S, which serves as a bearing for one end of a rock-shaft T, the opposite end thereof being supported in a bearing-block w secured to a cross-brace x of the hounds, this rock-shaft carrying a detent lever U, which operates in connection with the segment, and in conjunction with an arm V fast on said rock-shaft serving as a raising and lowering means for the cutting-apparatus.

35 The upper arm of sleeve b of the cutting-apparatus has secured thereto a cross-bracket y having an ear z that is linked to the arm V of the raising and lowering mechanism, whereby said cutting apparatus may by the detent-lever be lifted during transportation of the machine, and dropped to its working-position in the field. A similar mechanism for regulating the elevation of the cutting-apparatus is also provided for the purpose of controlling the disk with relation to its work while in operation. This mechanism comprises a foot-lever W, that is pivoted to the opposite hound from that on which the segment is secured, the short arm of the lever being connected to a chain or cable a' which passes over a guide-pulley b' mounted upon said hound. The chain or cable is then connected to a yoke X carried by the sleeve b of the cutting-apparatus.

50 By the above described foot-controlling means the operator may raise or lower the cutting-apparatus instantly as the case may require, and thus obtain perfect control of the machine to produce the best results.

55 In practice it has been found that in the growing of beets, owing to various conditions, they mature in some locations with the bulb exposed much higher from the ground than that in others, the stock above the ground being comparatively useless for some purpose. It is desirable to provide means for adjusting the height of cut in accordance with the will of the operator. To accomplish the above results a feed and supporting roller A' having lag-strips e'', is mounted in the yoke X in advance of the cutting disk, the yoke being pivot-ed at the rear end of the sleeve b, by a bolt d'' passing

through the yoke ends and ears projecting from said sleeve.

Positive adjustment of the yoke and its roller A' is obtained by bolts e'', which connect said yoke-arms with the cross-bracket y by means of nuts f' in threaded engagement with the bolts, there being springs g' interposed between said yoke and cross-bracket so as to spread the parts when the bolts are lengthened by adjusting the nuts, and also form a slight yield between the roller and cutting disk. 75

By the above described arrangement, the roller can be adjusted to any height with relation to the forward cutting-edge of the disk, and owing to the position of the roller in advance of said disk, the former will ride over the beets and thus regulate the depth of cut. The 80 said roller also is positively driven by means of a small sprocket wheel h' fast on the roller-shaft, in link-belt-connection with a large sprocket-wheel i' secured to the main axle, the peripheral speed of the roller being faster than the forward travel of the machine, whereby 85 said roller not only regulates the depth of cut, but also has a pulling feed action of the beet-tops towards the cutting edge of the disk, and thereby insures gathering the leaves in bunches to be severed this feature being important in order to get a clean cut should the leaves 90 be damp or flattened out through climatic conditions.

To insure the tops being delivered to the elevator, a spring-toothed reel B' is mounted above the roller k thereof, having one of its bearings in a standard j' projecting from the elevator-frame and its other bearing in 95 a depending arm k' of the cross-bracket y, the reel-shaft being driven by a bevel-pinion l' in mesh with the bevel-gear F on the arbor E of the cutting-apparatus.

As shown, suitable idle-rollers m' m'' are secured to 100 the yoke and sleeve b of the cutting-apparatus to support the drive-chain of the feed-roller in order to prevent said chain in its rotation from disengagement with its sprockets.

It will be understood from the preceding description that in operation the beets and their tops will be drawn 105 towards the cutting-disk by the increased speed of the feed-roller and severed, thereafter being thrown upon the elevator which delivers them to the carrier that may be dumped at the will of the operator. If desired however it is obvious that the carrier and elevator in some 110 instances can be dispensed with, in which case the several beet tops will be thrown upon the ground directly to one side of the disk, the stripper being then connected to the main frame of the machine, and while I have shown one method of obtaining the drive of the 115 cutting-disk from the main axle, it is obvious that any gear connection can be utilized for this purpose within the knowledge of the skilled mechanic, the essential features of my machine being the adjustment of the disk with relation to work, the adjustable feed-roller, said 120 roller being driven at a higher peripheral speed than the travel of the machine and the peculiar construction of the cutting-teeth of the disk.

I claim:

1. A beet-topping machine comprising a truck consisting of traction-wheels, axle and main frame supported upon the axle, a forward extension projecting from the frame, a supporting-roller for said forward extension, a horizontally disposed driven cutting disk carried by the aforesaid forward extension and to the rear of the roller, 125 fingers located upon the upper face of the disk, a sta-

tionary stripper interposed between the fingers and upper disk face, a draft-rigging in connection with the truck, and means in connection with the draft-rigging and aforesaid forward extension of the main-frame, whereby the 5 latter is raised or lowered.

2. A beet-topping machine comprising a truck consisting of traction-wheels, axle and main-frame supported upon the axle, a forward extension projecting from the frame, a supporting-roller for said forward extension, a 10 horizontally disposed driven cutting-disk carried by the aforesaid forward extension and to the rear of the roller, fingers located upon the upper face of the disk, a driven-elevator disposed to one side of the disk, a draft-rigging in connection with the truck, and means in connection with the 15 draft-rigging and aforesaid forward extension of the main-frame, whereby the latter is raised or lowered.

3. A beet-topping machine comprising a truck consisting of traction-wheels, axle and main-frame supported upon the axle, a forward extension projecting from the frame, an adjustable supporting roller for said frame-extension, a driven cutting-disk carried by the aforesaid frame-extension, a draft-rigging and main-frame, whereby the latter is raised or lowered. 20

25

25

25

4. A beet-topping machine comprising a truck consisting of traction-wheels, axle and main-frame supported upon the axle, a forward extension projecting from the frame, a shaft mounted in the forward frame extension, in gear-connection with the truck-axle, a vertically disposed 30

35

arbor carried by said frame-extension in gear-connection with the shaft, a cutting-disk secured to the arbor, a yoke in adjustable connection with the aforesaid frame-extension, a driven feed-roller carried by the yoke forward of the cutting-disk, a draft-rigging in connection with the truck, and means in connection with the draft-rigging and 40 forward frame-extension whereby the elevation of the latter is regulated.

5. A beet-topping machine comprising a truck consisting of traction-wheels, axle and main-frame supported upon the axle, a forward downwardly inclined extension 45 projecting from the main-frame, a shaft in bevel-gear connection with said axle carried by the extension, a vertically disposed arbor supported by said extension in bevel-gear connection with the shaft, a concavo-convex cutting-disk carried by the arbor, radial fingers disposed above the 50 disk, a stationary stripper for the fingers, a yoke adjustably connected to the aforesaid forward frame-extension, a supporting and feed-roller carried by the yoke forward of the cutting-disk, sprockets secured to the roller and axle of the machine in chain-belt connection for driving said roller, a draft-rigging in connection with the truck, a detent lever carried by the draft-rigging in link-connection with the forward frame-extension, and a supplementary foot-lever in connection with said frame extension, whereby the elevation of the cutting-disk may be 55 controlled. 60

In testimony that I, claim the foregoing I, have hereunto set my hand at S. Germantown in the county of Washington and State of Wisconsin in the presence of two witnesses.

LUDWIG GETTELmann.

Witnesses:
